JOSEPH W. DICKINSON, OF CRANFORD, NEW JERSEY, ASSIGNOR TO THE SCHUBERT PIANO COMPANY, OF NEW YORK, N. Y., A CORPORATION OF NEW YORK.

SHEET-GUIDING MECHANISM.

1,194,725.

Specification of Letters Patent. Patented Aug. 15, 1916.

Application filed April 22, 1911, Serial No. 622,812. Renewed May 4, 1915. Serial No. 25,842.

To all whom it may concern:

Be it known that I, JOSEPH W. DICKINSON, a citizen of the United States, residing at Cranford, in the county of Union and State of New Jersey, have invented certain new and useful Improvements in Sheet-Guiding Mechanism, of which the following is a specification.

This invention relates to improved means for guiding sheets or webs, such for instance as music sheets or webs, the object of the invention being to provide an improved mechanism of this character extremely simple in its construction and operation and comparatively inexpensive to manufacture and durable in use, and by means of which the music sheet will be automatically maintained in its proper position relatively to the tracker board, so that the perforations of the sheet will coincide or track with the corresponding apertures of the tracker board or bar at all times during the playing of the musical instrument, and which mechanism may be readily adjusted to correspond with different widths of music sheets.

In those forms of self playing musical instruments in which a perforated music sheet is used passing over a tracker board these music sheets, as is well known, are usually mounted on spools and perforated to correspond with perforations in the tracker board or bar over which the sheet is caused to travel, the sheet being unwound from one roll on to another. In consequence, any error in the alinement of the spools or in their construction, or any imperfection in the width of the sheet by reason of the fact that it has not been properly cut or trimmed, or because the same is not properly wound, or when the width of one sheet is different from that of another, as well as many other causes too numerous to need detailed mention, frequently causes the sheet to travel transversely out of its proper position so that the perforations in the sheet do not correctly or properly coincide with the apertures or openings in the tracker board or bar, this resulting in the production of imperfect music. Therefore, to automatically maintain the sheet in its proper tracking position I have provided improved means which, as herein-

before stated, is very simple in its construction and operation and which will effectively maintain the sheet during its passage over the tracker board in its proper tracking position, and which means may be readily adjusted to correspond with various widths of sheets, so that the sheet during its traveling movement will be automatically maintained in its proper tracking position regardless of any imperfections in the sheet or differences in the width thereof.

I am aware that various means have been used to maintain the traveling sheet in its proper position, but those mechanisms of which I am aware are not only more or less complicated, but are usually incapable of use with different widths of music sheets and none of them have the advantages of the present improvement for the reason that none of them have a movable or adjustable port located away from the sheet, or such a port controlled by a valve having contact with the sheet or web, whereby important advantages are obtained.

In the drawings accompanying and forming part of this specification, Figure 1 is a perspective view of a self playing pianoforte, with parts of the casing broken away to illustrate the present improvement attached thereto; Fig. 2 is a perspective view of the sheet guiding mechanism; Fig. 3 is a detail view of the movable port and its valve; Fig. 4 is a view of a pneumatic or bellows which is utilized in the present embodiment of the apparatus; and Fig. 5 is a diagrammatic view illustrating the music sheet in different transverse positions thereof as it passes over the tracker board.

Similar characters of reference indicate corresponding parts throughout the figures of the drawings.

The present improvement is particularly adapted for self playing instruments, and in the present embodiment thereof is shown constructed for such a purpose, and may be carried by a suitable casing or support which may be attached within the casing of the pianoforte. This casing 2, which may be of any suitable or desired construction, supports a pair of music rolls 3 and 4, the roll or spool 3 usually carrying the record or

music sheet which is to travel over the perforated tracker board 5 when the same is wound upon the companion roll or spool 4. For unwinding the sheet from one roll to the other suitable mechanism well known in this art is used, and therefore a general description thereof only is deemed necessary herein.

The music roll 3 is supported at one end by a journal or shaft 6 mounted in suitable bearings, and this shaft 6 carries a sprocket wheel 7 connected by a suitable sprocket chain 8 with another sprocket wheel 9 on a shaft 10 supported by the frame work. On this shaft is mounted a pinion 12 having a pin 13 therein forming one member of a clutch member 13', a corresponding pin, not shown, carried on the sprocket 9 forming the other member of the clutch. Motion is imparted to the shaft 10, which is a sliding shaft, by a sprocket 11. When the shaft is in position shown in Fig. 2 the pinion 12 is in engagement with the gear 14, thereby rotating the roll 4 and unwinding the music web from the roll 3. When the lever for shifting this shaft 10 is brought to the right the pinion 12 is disengaged from the gear 14 and the clutch pin 13 will engage the pin on sprocket 9, at which time it will be seen that the roll 3 is winding up the music from the roll 4. The sprocket 9 is loosely mounted on the shaft 10 and held in lateral position by the guide finger 10'. Between these rolls 3 and 4 is located the usual tracker board 5, having the usual perforations 16 with which the perforations in the record or music sheet coincide.

The shaft 6 is supported by the frame work for longitudinal movement, the end thereof projecting into position to engage an arm 17 carried by a bellows 18 secured to the frame work. The opposite end of the roll 3 is supported by a spring pressed plunger or journal 19 by means of which the roll 3 will be maintained in such position that the end of the shaft 6 will be held in engagement with the arm 17 of the bellows. Pivotally carried by the frame work is a pair of levers 20 and 21, the lever 20 carrying the movable or adjustable port, and for this purpose it is provided with an opening 22 to which a tube 23 leading from the bellows 18 hereinbefore referred to is connected. In the present instance this opening is formed by a short pipe carried by the end of the lever and to which a flexible tube is connected. The lever 21 is pivoted adjacent to the lever 20 and one end thereof forms a valve, as at 24, for controlling the port, a suitable spring 25 being located between the two levers, whereby the port will normally be maintained in a certain condition which in practice is a bleeding or leaking condition. The lever 20 is provided with a finger piece or handle 26 by means of

which it may be manipulated as occasion requires, such lever 20 being frictionally maintained in the desired position by means of a suitable set screw 20' and a coil spring 20''. Leading from the bellows to the usual pneumatic of the musical instrument is another tube 27, the opening thereinto from the bellows being somewhat smaller than that of the tube connecting the bellows with the movable port to permit proper operation of the bellows in a manner about to be described.

The lever 21 is in such position that it will engage the edge of the music sheet during its traveling movement from the roll 3 to the roll 4, so that if for any of the causes hereinbefore set forth the position of the sheet varies with relation to the tracker board the mechanism herein shown will automatically shift the sheet to have the perforations therein properly coincide with the perforations of the tracker board. For instance, if the sheet during its traveling movement moves to the left it will shift the lever 21 into the position shown in dotted lines in Fig. 3, thereby moving the valve and further opening the port and permitting atmospheric air more quickly to pass into the tube and from thence to the bellows, thereby expanding the same and causing the arm thereof to move away from the shaft 6, whereupon the spring actuated plunger at the opposite end of the roll 3 causes the roll to move toward the right so as to again bring the shaft 6 into engagement with the arm of the bellows and so return the sheet to its proper position relatively to the tracker board and at which time the valve will return to its normal position relative to the port. If, however, the sheet should crawl or move to the right, the valve would be shifted from its normal position to a position where it would close the port more than in the normal condition thereof and thus permit the gradual exhaust of the air from the bellows which would contract the same and cause the arm to shift the shaft 6 and thereby the music roll against the action of the spring actuated plunger into proper position to have the sheet travel in proper position over the tracker board. It is understood, of course, that by reason of the fact that the outlet from the bellows is of smaller diameter than the inlet thereto the air will pass therefrom with less rapidity than it passes thereinto. In practice, however, it is found that during the operation of the improvement, when the music sheet is traveling properly, that is normally tracking, the valve lever is maintained in such position that the port is slightly open so that it leaks or bleeds, and thus maintains the bellows properly balanced, and it is only when the sheet shifts out of its proper tracking position that the valve closes the

port entirely or opens it to a greater extent. The present improvement thus permits the use of a bleeding port to control the position of the sheet. When the valve is in other 5 than its normal position, in which of course the port is slightly open or leaking or bleeding, it will therefore be in a position where it closes the port more than such port is closed in the normal condition thereof or 10 where it closes such port less than in the normal condition thereof.

Should a music sheet of one manufacturer be narrower or wider than that of another the movable port may be adjusted and set to 15 a different position, so that when the valve is in its normal position the lever 21 will contact with the edge of the music sheet when the same is in its proper position to track, and therefore, as will be immediately apparent, the same mechanism is capable of 20 use with different widths of music sheets.

In practice, if preferred, the movable port and the valve controlling lever may be duplicated on the opposite side of the sheet, so 25 that movement of the sheet in either direction will operate the bellows through a movable port, and it will therefore be obvious that various modifications may be made and the details more or less varied without de- 30 parting from the spirit or scope of this invention.

In addition to the foregoing advantages for the present improvement, by providing a movable port the mechanism may be used 35 for transposing the music into different keys, that is, to a higher or lower key without the necessity of moving the tracker board or re-positioning the spools, this being accomplished by merely adjusting the 40 movable port to accord with the desired position of the roll relatively to the tracker board.

From the foregoing it will be therefore observed that not only is the present improvement automatically effective to properly guide the music sheet, but that it may also be used to transpose the music into a 45 higher or lower key by the mere adjustment of the port, and that the present improvement can be used on any width of music sheet by merely setting the guide lever so that it will engage the edge of the web or music sheet and then setting the movable port so that it will be properly positioned 50 relatively to the valve. It will, of course, be understood in practice that when the music is to be transposed into a different key the end of the sheet will be attached to the roll 4 nearer to one end or the other as the 55 case may be by any suitable means. For instance, the roll 4 may be provided with hooks 30 in staggered relation.

I claim as my invention:

1. In a musical instrument, the combination 60 with a permanently stationary tracker

board, of means operative to move the music sheet laterally and means for controlling the operation of said means including a single independently adjustable port free of contact with the sheet. 70

2. In a musical instrument, the combination with a permanently stationary tracker board, of means operative to move the music sheet laterally, means for controlling the operation of said means including a single independently adjustable port free of contact with the sheet, and means in engagement with the sheet and having a valve for controlling said port. 75

3. In a musical instrument, the combination with a permanently stationary tracker board, of means operative to move the music sheet laterally, means for controlling the operation of said means including a single independently adjustable port located away 80 from and free of contact with the sheet, and means in engagement with the edge of the sheet and having a single valve for controlling said port. 85

4. In a musical instrument, the combination with a permanently stationary tracker board, of a pair of rolls, means for winding a sheet from one roll to the other, means operative to move the sheet laterally by moving one of the rolls thereof, and means for 90 controlling the operation of said means including a single independently adjustable port located away from and out of contact with the sheet and freely adjustable at the will of the operator. 95

5. In a musical instrument, the combination with a permanently stationary tracker board, of a pair of rolls, means for winding a sheet from one roll to the other, means operative to move the sheet laterally by moving one of the rolls thereof, means for controlling the operation of said means including a single independently adjustable port located away from and out of contact with the sheet and freely adjustable at the will 100 of the operator, and means in engagement with the sheet and having a valve for controlling said port. 110

6. A music sheet guiding mechanism comprising means operative to move the sheet laterally and means for controlling the operation of said means including a movable port, an adjustable lever carrying said port, and means in engagement with the sheet and having a valve for controlling said port. 115 120

7. A music sheet guiding mechanism comprising means operative to move the sheet laterally and means for controlling the operation of said means including a movable port, an adjustable lever carrying said port, and means in engagement with the sheet and having a valve for controlling said port and comprising a lever in engagement with the edge of the sheet. 125

8. A music sheet guiding mechanism com- 130

- prising means operative to move the sheet laterally and means for controlling the operation of said means including a movable port, an adjustable lever carrying said port, 5 means in engagement with the sheet and having a valve for controlling said port and comprising a lever in engagement with the edge of the sheet, and a spring between said pair of levers.
- 10 9. In a musical instrument, the combination with a permanently stationary tracker board, of a pair of rolls, means for winding a sheet from one roll to the other, one of said rolls supported for lengthwise movement relatively to the other, a pneumatic having means in engagement with a part of said lengthwise movable roll, means for controlling the operation of said pneumatic including a single independently adjustable 15 port in communication with said pneumatic and supported free of contact with the sheet and freely adjustable at the will of the operator, and means in engagement with the sheet and having a single valve for controlling said port.
- 10 10. A music sheet guiding mechanism comprising a pair of rolls, means for winding the sheet from one roll to the other, one of said rolls supported for lengthwise movement relatively to the other, a pneumatic having means in engagement with a part of said lengthwise movable roll, means for controlling the operation of said pneumatic including an adjustable port in communication 20 30 35 40 45 50 55 60 65 70 75 80 85 90 95 100 105 110 115 120 125 130 therewith, and supported out of contact with the sheet, and means in engagement with the sheet and having a valve for controlling said port, said valve and said port each being carried by a lever, the lever carrying the adjustable port being adjustable into different positions.
11. A music sheet guiding mechanism comprising a tracker board, a pair of rolls, means for winding the sheet from one roll to the other, a bellows having an inlet and an outlet, the latter of smaller diameter than the inlet, means for supporting one of the rolls for lengthwise movement, means in engagement with said lengthwise moving roll and in position to be controlled by the expansion or contraction of the bellows, a port in communication with the inlet of said bellows and located away from the tracker board, and means in engagement with the sheet and carrying a valve for controlling said port.
12. A music sheet guiding mechanism comprising a tracker board, a pair of rolls, means for winding the sheet from one roll to the other, lengthwise shiftable journals for supporting the roll originally carrying the sheet, a spring for normally pressing said roll in one direction, a bellows having an inlet and an outlet, the latter of less diameter than the inlet, an arm carried by the
- bellows and in engagement with one of said journals, an adjustable port in communication with the inlet of said bellows and located away from the tracker board, and means in engagement with the sheet and having a valve for controlling said port.
13. A music sheet guiding mechanism comprising a pair of rolls, means for winding the sheet from one roll to the other, lengthwise shiftable journals for supporting the roll originally carrying the sheet, a spring for normally pressing said roll in one direction, a bellows having an inlet and an outlet, the latter of less diameter than the inlet, an arm carried by the bellows and in engagement with one of said journals, a movable port in communication with the inlet of said bellows, means in engagement with the sheet and having a valve for controlling said port, and a lever carrying said port and adjustable into different positions.
14. A music sheet guiding mechanism comprising a pair of rolls, means for winding the sheet from one roll to the other, lengthwise shiftable journals for supporting the roll originally carrying the sheet, a spring for normally pressing said roll in one direction, a bellows having an inlet and an outlet, the latter of less diameter than the inlet, an arm carried by the bellows and in engagement with one of said journals, a movable port in communication with the inlet of said bellows, means in engagement with the sheet and having a valve for controlling said port, a lever carrying said port and adjustable into different positions, the means carrying the valve comprising a lever in position to be engaged by the edge of the sheet, and a spring between said levers for maintaining the valve lever in engagement with the edge of the sheet.
15. A music sheet guiding mechanism comprising a pair of rolls, means for winding the sheet from one roll to the other, lengthwise shiftable journals for supporting the roll originally carrying the sheet, a spring for normally pressing the roll in one direction, a bellows having an inlet and an outlet, the latter of smaller diameter than the inlet, a movable port, a flexible tube connecting said port with the inlet of the bellows, a flexible tube connecting the outlet of the bellows with a pneumatic, said bellows having an arm in position to engage one of the lengthwise shiftable journals, an adjustable lever carrying said port, a shiftable lever in position to be engaged by the edge of the music sheet, and a spring for maintaining it in such position and said last lever having a valve for controlling said port.
16. A music sheet guiding mechanism comprising means operative to move the sheet laterally and means for controlling

- the operation of said means including a movable port, means in engagement with the sheet and having a valve for controlling said port, and means for maintaining said 5 valve carrying means in engagement with the edge of the sheet and comprising a spring, said port being carried by an adjustable lever and said sheet engaging means comprising a swinging lever.
- 10 17. A music sheet guiding mechanism including a permanently stationary tracker board and comprising means operative to move the sheet laterally and including a pneumatic, means for controlling the operation thereof including a single independently adjustable port located free of contact with the sheet, and means in engagement with the sheet and having a valve for controlling said port.
- 15 18. A music sheet guiding mechanism including a tracker board and a pair of rolls, means for winding the sheet from one roll to the other, means operative to shift one of the parts relatively to the other, means for 20 controlling the operation of said means including a single adjustable port supported free of contact with the sheet and independently of such shiftable part, and means in engagement with the sheet and having a single valve for controlling said port.
- 25 19. In a musical instrument, the combination with a permanently stationary tracker board, of music sheet guiding mechanism comprising means operative to move the sheet laterally in either direction including a bellows at one edge of the sheet, means for controlling the operation of said bellows including a single adjustable port, and means in engagement with the edge of the 30 sheet and having a valve for controlling said port, said bellows and sheet engaging means being located at the opposite edges of the sheet and the port away from and out of contact with the sheet.
- 35 20. In a musical instrument, the combination with a permanently stationary tracker board and with a traveling sheet or web, of means contacting with the web and held in its normal position when the web is 40 in its normal position and effective to restore the web to such normal position when deflected or distorted therefrom including a single adjustable port located away from and out of contact with the web and supported independently of the tracker board.
- 45 21. A music sheet guiding mechanism comprising a pneumatically operated device and an adjustable pivotally supported port connected therewith and located away from the sheet and controlled by means in engagement with the sheet.
- 50 22. A music sheet guiding mechanism comprising means automatically operative to move the sheet laterally, and means including a part in engagement with the sheet
- and movable laterally for governing said sheet moving means including a swinging port located out of contact with the sheet.
- 55 23. Means for controlling the position of a movable sheet or web, comprising a pair of pivotally supported devices, one having a port and one a valve for controlling said port, one adjustable relatively to the other and one shiftable relatively to the other and one carrying a part in engagement with the web, and means in communication with said adjustable device for controlling the movement of the web.
- 60 24. Means for controlling the position of a movable sheet or web, comprising a pair of pivotally supported devices, one having a port and one a valve for closing said port, one adjustable relatively to the other and one shiftable relatively to the other and one carrying a part in engagement with the web, and pneumatic means in communication with the adjustable device for controlling the movement of the web and having an inlet and an outlet of different diameters.
- 65 25. Means for controlling the position of a movable sheet or web and including a port, a valve for controlling said port, one shiftable and one adjustable, and both pivotally supported means carrying the shiftable member and in position to be engaged by the edge of the sheet or web, and a spring for maintaining it in engagement with the edge of the sheet or web.
- 70 26. Means for controlling the lateral movement of a moving sheet or web and comprising a pair of rolls, means for winding the web from one roll to the other, one of said rolls being supported for lengthwise movement, a pneumatic having direct contact with a part of said lengthwise movable roll for shifting the same lengthwise in one direction and having openings of different diameters, means for shifting it in the opposite direction, an adjustable port located away from and out of contact with the web and in communication with said pneumatic, and means in engagement with the web for controlling said port.
- 75 27. A music sheet guiding mechanism comprising a perforated tracker bar, sheet winding means carrying a perforated music sheet, means for shifting one of the parts relatively to the other thereby to insure the registration of the sheet perforations with those of the tracker bar, and means for controlling said shifting means and comprising a swinging port opening to the atmosphere and means in engagement with the sheet and movable thereby for controlling said port.
- 80 28. A music sheet guiding mechanism comprising means operative to move the sheet laterally, and means for controlling the operation of said means and comprising a lever carrying a port opening to the
- 125

atmosphere and a lever carrying a valve for controlling said port and having a part thereof in position to be engaged by the sheet.

5 29. In a musical instrument having a tracker board provided with a set of perforations and a pair of rolls for carrying a music sheet having another set of perforations, the combination of music sheet guiding mechanism comprising means operative to regulate the position of the part carrying one set of such perforations relatively to those of the other part, and means for controlling the operation of such regulating means including a single adjustable port, said port having a fixed position relatively to, but adjustable independently of, any of the moving parts of the instrument.

30. A music sheet guiding mechanism comprising pneumatically operative means to move the sheet laterally, and means for controlling the operation of said means and comprising an adjustable lever carrying a port opening to the atmosphere and a shiftable lever carrying a valve for controlling said port and having a part thereof in position to be engaged by the sheet, the said levers being so supported that on the adjustment of the port the sheet-engaging lever will be adjusted therewith.

31. In a musical instrument, the combination with a perforated tracker board and a pair of rolls for carrying a perforated music sheet, of sheet guiding mechanism comprising means operative to regulate the position of one set of such perforations relatively to the other, means for controlling the operation of said means including a swinging means carrying a single port and a valve for controlling said port and having a part in engagement with the sheet.

32. In a musical instrument, the combination with a perforated tracker board and a pair of rolls for carrying a perforated music sheet, of sheet guiding mechanism comprising means operative to regulate the position of one set of such perforations relatively to the other, means for controlling the operation of said means including a freely adjustable means having a part projecting crosswise of the plane of travel of the sheet and to the front of the tracker board in position to be adjusted at the will of the operator but otherwise fixed against movement and carrying a port, and a valve for controlling said port and having a part in engagement with the sheet.

33. In a musical instrument, the combination with a perforated tracker board and a pair of rolls for carrying a perforated music sheet, of sheet guiding mechanism comprising means operative to regulate the position of one set of such perforations relatively to the other, means for controlling the operation of said means including a freely ad-

justable means having a handle and in position to be adjusted at the will of the operator but otherwise fixed against movement and carrying a single port, and a single valve for controlling said port and having a part in engagement with the sheet.

34. In a musical instrument, the combination with a perforated tracker board and a pair of rolls for carrying a perforated music sheet, of sheet guiding mechanism comprising means operative to regulate the position of one set of such perforations relatively to the other, means for controlling the operation of said means comprising a freely adjustable member carrying a port and in position to be adjusted at the will of the operator but otherwise fixed against movement, and a valve member for controlling said port and having a part in engagement with the sheet, said port and valve members each projecting crosswise of the plane of travel of the sheet and to the front of the tracker board for operation.

35. In a musical instrument, the combination with a perforated tracker board and a pair of rolls for carrying a perforated music sheet, of sheet guiding mechanism comprising means operative to regulate the position of the sheet perforations relatively to the tracker board by moving said sheet laterally relatively to the tracker board, means for controlling the operation of said means including an adjustable member carrying a port and in position to be adjusted at the will of the operator but otherwise fixed against movement, and a valve member for controlling said port and having a part in engagement with the sheet, both said valve and port carrying members projecting crosswise of the plane of travel of the sheet and beyond the front plane of the tracker board for operation.

36. A music sheet guiding mechanism comprising a perforated tracker bar, sheet winding means carrying a perforated music sheet, means for shifting one of the parts relatively to the other thereby to insure the registration of the sheet perforations with those of the tracker bar, and means for controlling said shifting means and comprising a swinging port and means in engagement with the sheet and movable thereby for controlling said port.

37. A music sheet guiding mechanism comprising a perforated tracker bar, sheet winding means carrying a perforated music sheet, pneumatic means for shifting one of the parts relatively to the other thereby to insure the registration of the sheet perforations with those of the tracker bar, and means for controlling said shifting means and comprising a single swinging port and means in engagement with the edge of the sheet and movable thereby for controlling said port.

38. The combination with a sheet or web, of means including a pneumatic, a single adjustable port, and a movable valve member contacting with the edge of the web for holding said pneumatic in a certain position when the web is in its normal tracking position and for controlling the movement of the means which effects the restoration of the web to that normal position when deflected or diverted therefrom. 10
39. The combination with a music sheet or web, of means including a pneumatic, a port, and means contacting with the web and cooperating with said port for holding said pneumatic in a certain position when the web is in its normal tracking position and for guiding or restoring the web to that normal position when deflected or diverted therefrom. 15
40. The combination with a music sheet, of a port and a valve for controlling said port and engaged by the sheet for maintaining said port in a bleeding condition during the proper tracking of the sheet. 20
41. The combination with a music sheet, of a swinging adjustable port and a swinging valve for controlling the port and engaged by the edge of the sheet for maintaining said port in a bleeding condition during the proper tracking of the sheet. 25
42. The combination with a sheet or web, of means including a pneumatic, a port, and means contacting with the web for holding said pneumatic in operation and in its balanced position when the web is in its normal tracking position and for guiding or restoring the web to that normal position when deflected or diverted therefrom. 30
43. A music sheet guiding mechanism comprising a perforated tracker bar, shiftable winding means carrying a perforated music sheet, means for shifting one of the parts relatively to the other thereby to insure the registration of the sheet perforations with those of the tracker bar, and means for controlling said shifting means and comprising a bleeding port and means in engagement with the sheet and movable thereby for controlling said port. 35
44. A music sheet guiding mechanism comprising a perforated tracker bar, sheet winding means carrying a perforated music sheet, pneumatic means for shifting one of the parts relatively to the other thereby to insure the registration of the sheet perforations with those of the tracker bar, means for controlling said shifting means and comprising a single adjustable bleeding port, and means in engagement with the sheet for controlling said port. 40
45. The combination with a music sheet, of a pivotally supported lever carrying a port, and a pivotally supported lever carrying a valve for maintaining said port in a bleeding condition when the sheet is nor- 45
- mally tracking and having a part in engagement with the sheet. 50
46. The combination with a music sheet, of a pivotally supported lever carrying a port, and a pivotally supported lever carrying a valve for maintaining said port in a bleeding condition when the sheet is normally tracking and having a part in engagement with the edge of the sheet. 55
47. A music sheet guiding mechanism comprising a perforated tracker bar, shiftable winding means carrying a perforated music sheet, means for shifting one of the parts relatively to the other thereby to insure the registration of the sheet perforations with those of the tracker bar, means for controlling said shifting means and comprising an adjustable bleeding port, and means in engagement with the sheet and movable thereby for controlling said port. 60
48. A music sheet guiding mechanism comprising a perforated tracker bar, shiftable winding means carrying a perforated music sheet, means for shifting one of the parts relatively to the other thereby to insure the registration of the sheet perforations with those of the tracker bar, means for controlling said shifting means and comprising a swinging bleeding port, and means in engagement with the sheet and movable therewith for controlling said port. 65
49. A music sheet guiding mechanism comprising a perforated tracker bar, sheet winding means carrying a perforated music sheet, pneumatic means for shifting one of the parts relatively to the other thereby to insure the registration of the sheet perforations with those of the tracker bar, means for controlling said shifting means and comprising a single adjustable bleeding port, and means in engagement with the sheet for controlling said port. 70
50. A music sheet guiding mechanism comprising a perforated tracker bar, sheet winding means carrying a perforated music sheet, pneumatic means for shifting one of the parts relatively to the other thereby to insure the registration of the sheet perforations with those of the tracker bar, means for controlling said shifting means and comprising a single swinging bleeding port, and means in engagement with the sheet for controlling said port and comprising a single swinging valve. 75
51. A music sheet guiding mechanism comprising a pneumatically operated device, an adjustable pivotally supported port connected therewith and located away from the sheet, and means in engagement with the sheet for maintaining said port in a bleeding condition during the normal traveling of the sheet. 80
52. A music sheet guiding mechanism comprising means for controlling the position of a movable sheet or web and compris- 85
